UNITED STATES PATENT OFFICE.

OSCAR V. PAYNE, OF CLEVELAND, OHIO, ASSIGNOR TO AUTO-ORDNANCE CORPORATION, OF NEW YORK, N. Y., A CORPORATION OF NEW YORK.

GUN.

1,347,756.

Specification of Letters Patent. Patented July 27, 1920.

Application filed January 24, 1920. Serial No. 353,704.

To all whom it may concern:

Be it known that I, OSCAR V. PAYNE, a citizen of the United States, and resident of Cleveland, in the county of Cuyahoga and State of Ohio, have invented new and useful Improvements in Guns, of which the following is a specification.

This invention relates to guns, particularly automatic guns of the smaller types such as rifles and machine guns, more particularly to guns of the type having a breech closure reciprocatable rearwardly and forwardly and rotatable into locked position at the forward end of its stroke, and still more particularly to guns operating according to the discovery set forth in the patent to Blish 1,131,319, granted March 9, 1915, wherein the receiver and breech closure are provided with locking abutments inclined to the line of breech pressure at such angle that the closure is held closed during high breech pressure but is automatically unlocked directly in response to the breech pressure acting through the closure when the pressure decreases to a relatively low value.

In automatic guns of the type referred to, having a reciprocatory breech closure arranged to rotate into locked position at the forward end of its stroke, the purely reciprocal movement of the closure during its recoil must be quickly changed into a combined reciprocal and rotary movement at the end of its forward stroke and vice versa as the closure unlocks and opens, especially in rapid fire guns where the cycle of operation is repeated many times per second. Heretofore, cams or guides have been provided on the receiver in the path of lugs on the closure, the guides extending obliquely to the line of reciprocation to throw the closure into locked position at the end of its forward stroke, other guides being provided to stop the rotation in unlocking and to guide the closure in its recoil movement. With such an arrangement a sharp impact results each time the lugs strike the oblique cams or guides at the forward end of the stroke and a still sharper impact results each time the lugs strike the longitudinal guides in the unlocking rotation of the closure. These impacts cause excessive wear and frequent breakages and mitigate against accurate firing.

Another difficulty encountered in guns of the aforesaid type is that of forming the

locking abutments on the bolt and more especially in the receiver, and of making these abutments of sufficient strength to withstand the wear and tear of the breech pressures, these pressures rising to the order of fifty thousand pounds per square inch in military rifles for example.

Furthermore it is essential that the weight of military firearms and other portable guns be minimized to the greatest possible extent.

Moreover, in guns of the aforesaid type it is desirable to have one or more lugs or projections extend outwardly from the breech mechanism through slots in the receiver to control the breech mechanism, and in order to exclude dust and other foreign matter it is essential that these slots be closed.

Another difficulty experienced in guns of the type referred to is that of securing uniform and reliable action. While known guns of this type will function well at times, they frequently function erratically or not at all. I have discovered that this difficulty can be overcome by uniformly lubricating the contacting surfaces between the locking abutments of the receiver and breech closure and that this lubrication does not destroy the locking qualities of the abutments at high breech pressure, as would be expected, presumably for the reason that the film of lubricant between the abutting surfaces is momentarily squeezed into the interstices of the abutments during the infinitesimal interval of high breech pressure.

The principal objects of the present invention are to overcome the aforesaid and other difficulties and to provide the aforesaid and other essentials. More particular objects are, viz.: smoothly to blend the reciprocal and rotary movements of the breech closure so as practically or wholly to eliminate the aforesaid impacts and the wear and other disadvantages incident thereto; to provide interlocking abutments on the breech closure and receiver which may be manufactured with facility and at a low cost, and which have extensive bearing surfaces and great strength, and at the same time low weights; to provide a gun which is lighter than known guns of like capacities and capabilities but which is more durable and safe; to provide means for automatically closing the slots or other openings provided in the receiver for projecting parts

of the breech mechanism, thereby to exclude dust and other foreign matter from the working mechanism of the breech action; to provide means for lubricating the locking abutments of the receiver and breech closure and other sliding parts of the mechanism so as to render the automatic action of the breech mechanism uniform and reliable and to reduce the wear; and generally to improve the construction and operation of guns of the aforesaid types.

The invention consists in providing guns of the aforesaid types with an interfitting lug and guideway on the bolt and receiver respectively (or vice versa) for guiding the movements of the bolt, the guideway having a longitudinal portion and a transverse portion tangentially connecting with the longitudinal portion throughout a gradual and uninterrupted bend so that the rotation of the closure into and out of locked position blends with its reciprocation smoothly and without impact, and the lug and guideway being coördinated with the locking abutments so that the abutments are guided into and out of locking engagement throughout a smoothly curving path without subjecting the abutments to impacts or other forces. I have discovered that these results cannot be satisfactorily attained without extending said bend circumferentially throughout a relatively wide angle, preferably at least of the order of 40° (in a gun with two sets of locking abutments) and this angle is not available in known guns in which the total angle of bolt rotation is only 90° or less. I therefore propose to interrelate the guiding lug and guideway with the locking abutments so that the bolt may be rotated through a much wider angle, preferably at least of the order of 110° , thereby affording an angle of 40° *e. g.* for blending the rotation into the reciprocation and a further angle of 70° *e. g.* for interengaging the abutments. This involves a novel arrangement of the locking lugs or abutments on the bolt relative to those on the receiver whereby the two sets are angularly spaced from each other in the unlocked position of the bolt by an angle approximately equal to the angle of said bend, that is, 40° in the example stated.

The invention also involves a shutter for closing the aforesaid slot or slots in the receiver, the shutter being non-reciprocatable but rotatable with the bolt to close the slots when the bolt is in locked position and having one or more longitudinal slots to accommodate the lugs or other parts projecting from the breech mechanism outwardly through the receiver. The shutter preferably comprises a tube fitting in the receiver between the bolt and the inner wall of the receiver.

Another feature of the invention consists in forming the receiver into two parts, preferably tubular, fitted together end to end, and in forming said guideway in the form of intercommunicating slots in the two parts. The forward part is provided with the locking abutments and the inclined portion of the guideway slot, and is made sufficiently heavy to withstand the stresses set up by the breech pressure. The locking abutments are preferably formed on a cylindrical sleeve or tubular member adapted to be threaded or otherwise secured in said forward part of the receiver. The rearward part of the receiver is arranged to serve merely as a recoil housing and guide for the breech bolt and may therefore be made relatively thin and light. Indeed it is preferably formed as a thin tube of pressed metal, closed at its rearward end to confine the recoil spring and threaded at its forward end to thread into the forward part of the receiver in abutting relationship with said locking sleeve. The shutter is also preferably formed as a pressed-metal tube adapted to fit within said rearward tubular part of the receiver with its forward and rearward ends abutting respectively against said locking sleeve and said closed end of the rearward part of the receiver.

The forward part of the receiver and said locking sleeve are provided with lubricant ducts leading to the abutting surfaces of the locking abutments, wicks or other suitable lubricant feeding means being associated with these ducts to afford a uniform lubrication of the surfaces. By supplying lubricant to the breech mechanism in this unique manner the lubricant may be transmitted to a part or all of the sliding surfaces of the breech mechanism, in addition to the locking surfaces, by being carried along the sliding surfaces as the parts slide back and forth or by being supplied in such quantity as to flow over the surfaces.

Other improvements herein disclosed, such as the firing pin, trigger mechanism, combined magazine and trigger guard, etc., are not claimed in the present application and will herein be described only in connection with the specific embodiment of the invention illustrated in the accompanying drawings, in which—

Fig. 17 is a top plan of the forward end of the rearward part of the receiver.

25 The particular embodiment of the invention chosen for the purpose of illustration comprises in general a stock 1, a barrel 2, a receiver formed in forward and rearward parts 3 and 4, a heat guard 5 surrounding the rear end of the barrel 2, the guard 5 being insulated from the receiver by suitable non-conducting material 91, and a frame member 6. The forward portion 3 of the receiver comprises substantially cylindrical

30 forward and rearward ends joined together by side walls 9 and 10, the forward end being threaded over the barrel and the rearward end being provided with internal threads to receive the locking sleeve 11 and the rearward portion 4 of the receiver. A clip holder 92 is provided to facilitate loading the magazine from the top as in the Springfield rifle. An ejection opening 13 is provided on the right-hand side as shown in Fig. 5. The frame member 6 is preferably formed of aluminium alloy or other light metal, and has the magazine chamber 14 and also the trigger guard 15 formed integrally therein. The frame member is connected to

40 the forward part 3 of the receiver by means of screws 16 and 17, the screw 17 having an axial lubricant duct extending therethrough, and having a lubricant cup 18 threaded thereover.

45 The locking sleeve 11, which is preferably formed of bronze, or other high pressure bearing material, is adapted to be threaded into the part 3 of the receiver from the rear. The locking sleeve is provided on its inner periphery with upper and lower sets 50 19 and 20 of locking lugs which extend radially inwardly, the lugs of each set being disposed in alignment longitudinally of the gun. The forward faces of these locking 55 lugs are inclined circumferentially with re-

spect to a plane perpendicular to the axis of the gun at such angles that the bolt lugs abutting thereagainst will be locked thereto during high breech pressure but will slide thereover due to the circumferential obliquity of the contacting faces when the pressure drops to relatively low value, thereby automatically unlocking the bolt according to the discovery in the aforesaid patent to Blish. Each set of lugs 19 and 20 extends circumferentially throughout an angle considerably less than 90°, so as to leave circumferential spaces 21 and 22 (Fig. 10) therebetween of substantially greater circumferential extent than 90°, preferably at 60 least 110°.

The rear portion 4 of the receiver is preferably formed as a cylindrical tube closed at its rearward end and provided with four, more or less, sets of mutilated threads at its 65 forward end adapted to engage with the same number of sets of mutilated threads in the rear end of the forward portion 3 of the receiver. Disposed in the rearward end of the tube 4 is a buffer comprising a rearward portion 23 and a forward portion 24 telescoping over the rearward portion, the space within the two portions being filled with disks 25 of leather or the like, and the two portions being connected together by a 70 small rod 26 adapted to be compressed or flexed by impacts on the forward end of the buffer.

The two portions 3 and 4 of the receiver are provided with intercommunicating slots 75 27 and 28, the slot 28 extending longitudinally of the rearward portion 4, and the slot 27 bending circumferentially to the right and connecting tangentially with the slot 28 as shown in Fig. 2. The inclined 80 portion 27 of the slot bends gradually away from the longitudinal part 28 through a circumferential angle of approximately 40° and then continues at substantially a constant angle to a plane perpendicular to the 85 axis of the gun through an angle of substantially 70°. The forward portion 3 of the receiver is reinforced on opposite sides of the portion 27 of the slot 6 shown in 90 Figs. 3, 4 and 6.

115 Rotatably fitted within the rear portion 4 of the receiver is a tubular shutter 29 abutting at its rearward end against the rear end of the tube 4 through the base of the buffer, and abutting at its forward end 120 against the rear end of the locking sleeve 11. This sleeve is provided with a longitudinal slot 30 adapted to register with the longitudinal slot 28 in the receiver when the bolt is in unlocked position. The tube 29 is also 125 provided with a longitudinal slot 31 opposite to the slot 30, the slot 31 being adapted to register with the slot 32 in the lower side of the part 4 of the receiver when the bolt is in unlocked position. The slot 31 is pro- 130

vided with an offset portion 33 extending in a counterclockwise direction therefrom at the forward end of the tube for a purpose hereinafter described.

5 The bolt unit comprises a cylindrical bolt 34 having an enlarged rearward portion 35 adapted to slide in the tube 29, the forward portion of the bolt being adapted to slide along the inner faces of the lugs on the 10 locking sleeve 11. The bolt is provided at its forward end with an extractor 36 which is held on the bolt by means of a band 36^a (Fig. 6) fitting in groove 41 (Fig. 14) in the bolt. The extractor is provided with a 15 lug 93 adapted to ride in a groove 90 in the receiver and locking sleeve, this lug serving to keep the extractor in line with the notch provided in the barrel for the forward end thereof. Extending radially 20 from the rearward end of the bolt is an actuating lug 37, this lug extending outwardly through the slots 28 and 30 in the tubes 4 and 29. Immediately in advance of the enlarged head 35 are two sets of lugs 25 38 and 39 adapted to interengage with the lugs 19 and 20 on the locking sleeve 11 when the bolt is in locked position, the abutting faces of these lugs facing rearwardly in opposition to the forwardly facing lugs on the 30 locking sleeve. The forward end of the bolt is provided with a longitudinal slot 40 (Fig. 14) decreasing in depth from front to rear and vanishing a short distance in front of the groove 41 for the extractor, the groove 40 being adapted to receive the ejector hereinafter described. The head 35 of the bolt is provided with a rearwardly facing cam 42 extending circumferentially of the bolt through an angle of approximately 110° for the purpose of retracting the firing member in the unlocking movement of the bolt as hereinafter described.

The bolt 34 is provided with an axial chamber whose diameter decreases from the rear to the front by steps, and within this opening the firing pin 43 is arranged both to rotate and to reciprocate relatively to the bolt. The firing pin bears directly on the bolt at the forward end, and at the rearward end it bears in a sleeve 44 threaded into the rearward end of the bolt. The firing pin is provided with a depending lug 45 adapted to extend downwardly through the slots 31 and 32 in the tubes 55 4 and 29, the lug 45 being provided with a beveled cam face 46 adapted to be engaged by the cam 42 on the bolt.

A feature which I believe to be novel but which I do not claim in the present application, involves a simplified means for mounting the firing pin spring 47 on the firing pin. This means comprises a collar 48 formed integrally with the firing member and provided with an oblique slot 49 (Fig. 6), the forward end of the firing pin spring 47

being contracted so as to engage behind this collar. By virtue of the oblique slot 49, the contracted end of the spring 47 may be threaded over the collar 48 from the front in assembling the spring on the pin, 70 the firing pin first having been inserted through the sleeve 44. After the firing pin unit is thus assembled, the sleeve 44 is threaded into the rearward end of the bolt.

The breech closure is yieldingly urged 75 forwardly by a recoil spring 50 which fits loosely within the inner tube 29 and around the buffer 24. The recoil spring is anchored to the bolt at 51 and to receiver at 52, and in putting it in place it is subjected to a 80 torsion which tends to turn the bolt in a clockwise direction into locking position.

The ejector comprises a tubular member 53 closed at its inner end and provided with a flat nose 54 extending centrally from 85 the closed end (Figs. 5, 7 and 8). This ejector is adapted to extend radially through an opening 55 in the left side of the forward part 3 of the receiver (Figs. 3 and 5). The opening 55 extends through the receiver in 90 the region where the receiver changes in internal diameter, somewhat more than the rear half of the opening extending through the portion of larger internal diameter and somewhat less than the forward half ex- 95 tending through the portion of lesser internal diameter. The opening is extended only through the wall of larger internal diameter, thereby leaving shoulders 56 perpendicular to the axis of the opening in 100 the portion of smaller internal diameter. The closed end of the ejector 53, on opposite sides of the nose 54, is adapted to seat against these shoulders 56 to limit the inward movement of the ejector, the nose 54 105 being adapted to extend through a slot 57 in the portion of smaller internal diameter. The ejector 53 is yieldingly urged inwardly by a coil spring 58 which seats at its outer end against the bottom of a recess provided 110 in the catch 59 in radial alignment with the tubular ejector.

The catch 59 is secured to the receiver by means of a threaded stud 60, this stud having a smooth extension adapted to extend into an opening in the sleeve 11 to lock the sleeve in the receiver. Extending rearwardly from the stud 60 is a flexible arm provided with a lug 61 adapted to seat in an opening in the receiver, the rearwardly 120 extending arm being sufficiently flexible to disengage the lug from the opening while the stud 60 is being threaded into or out of the receiver. The spring recess in the forward end of the catch 59 opens downwardly 125 through an opening 62 in the lower side of the catch which is of substantially the same width as the diameter of the recess and which is substantially concentric with the axis of the stud 60.

In assembling the ejector and catch, the catch is first secured to the receiver by threading the stud 60 into the receiver, the catch being rotated slightly in advance (in 5 a clockwise direction in Fig. 9) of its normal position, the ejector 53 is inserted into the opening 55, the spring 58 is seated in the axial recess of the ejector, and the catch 59 is then rotated in a counterclockwise direction 10 into the normal position where the ejector slidingly fits in the recess in the forward end of the catch and where the lug 61 snaps into the opening provided therefor in the receiver.

15 In operation, the nose of the ejector rides on the periphery of the cylindrical bolt until the slot 40 (Fig. 14) reaches the ejector in the recoil of the bolt, whereupon the ejector nose rides down the inclined slot 20 under the influence of spring 58 into position to eject the empty cartridge case through the ejection opening 13. As the bolt moves forward, the ejector rides up the inclined groove 40 to the periphery of the 25 bolt, after which it rides on the periphery of the bolt, as the bolt continues its forward reciprocation and then rotates into locked position.

The firing mechanism comprises a trigger 30 63, a trigger bar 64, a safety catch 65, a sear 66 and a disconnector 67. The trigger 63 is pivotally mounted in a frame 6 by means of pin 68. The trigger bar 64 has a notch 69 (Figs. 15 and 16) at its rearward end 35 adapted to receive the hooked upper end of the trigger, and the trigger bar is yieldingly urged rearwardly by means of coil spring 69^a abutting against a transverse web 70 of the frame 6 at its forward end and 40 abutting the trigger bar at its rearward end (Fig. 16). The trigger bar 64 is fitted loosely through an opening in the transverse web 70 of the frame 6 so that it may be inserted therein after the trigger has 45 been assembled and so that it may be moved upwardly and downwardly at its forward end after insertion, a spring 71 being provided yieldingly to urge it upwardly. The sear 66 is formed as a bell crank pivoted on 50 the transverse pin 72 which is journaled at its opposite ends in depending lugs 75 (Fig. 3) on the receiver. The sear is normally urged in a counterclockwise direction by the sear spring 73 which seats on the upper end of the safety catch 65. In the normal position shown in the drawings, the sear is adapted to engage the depending lug 45 of the firing member to retain the firing member in retracted position. The disconnector 67 comprises a pin extending through a vertical opening in the sear and thence through a vertical opening in the receiver and locking sleeve. The upper end of this pin is rounded and engages a peripheral cam 74 (Figs. 10 and 12) on the bolt, and

the pin is provided with an integral collar intermediate its ends, this collar being adapted to engage the receiver and prevent the pin from sliding too far into the receiver chamber when the gun is inverted 70 while the bolt is removed, and from being lost through the sear during mounting and dismounting.

The safety catch (Figs. 4, 6, 13, 15 and 16) comprises a cylindrical portion 75 surmounted by a flange 76 adapted to rest on the upper surface of the frame 6. The catch is provided with a flat narrowed portion 77 extending downwardly through the frame member by means of which the catch may 80 be rotated, and with lugs 78 on the flange 76 engaging in notches in the frame to maintain it in safe and ready positions. The cylindrical portion 75 is provided with a transverse opening to receive the trigger 85 bar 64, and to limit its rotation, and the trigger bar is provided with a notch (Figs. 15 and 16) to hook over a shoulder of the catch when the catch is in the safe position shown in Fig. 15. The safety catch is also 90 provided with an upwardly extending lug 79 adapted to underlie the rear end of the sear in the safe position of the catch to prevent the sear from being moved into firing position due to jarring the gun. Thus, the 95 safety catch operates on both the trigger bar and the sear, thereby affording a double precaution against accidental firing.

The means for lubricating the abutting surfaces between the locking lugs has been 100 omitted in part in Figs. 4, 5 and 6 for the purpose of clearness, and the omitted parts are illustrated in Fig. 11. These parts comprise an annular duct 85 extending around the locking sleeve 11 in communication with the duct 80 leading through the screw 17 (Figs. 4 and 6), the annular duct 85 preferably being formed by cutting off one of the threads of the locking sleeve 11. Leading rearwardly from the annular duct 85 at the 105 top and bottom of the locking sleeve are two ducts 81 and 82 which extend almost to the rear of the locking sleeve, these ducts being cut into the outer periphery of the locking sleeve 11. Extending obliquely inwardly and forwardly from the ducts 81 and 82 are branch ducts 83 and 84 which lead to the abutting surfaces of the locking lugs. Thus lubricant may flow from the lubricant cup 18 through the axial duct 80 110 to the annular duct 85, thence rearwardly along the ducts 81 and 82, and thence inwardly through ducts 83 and 84 to the abutting surfaces.

The preferred means for assembling the 125 parts is as follows: In assembling the frame group the trigger is secured in the frame, the safety catch 65 is inserted into position in the frame 6 from the top, the disconnector spring 71 is inserted into its recess 130

from the top, the spring 69 is placed on the trigger bar, the trigger bar is inserted into the opening in the web 70 from the rear and thence through the safety catch 65, and 5 the rear end of the trigger bar is then interengaged with the trigger.

The receiver group is assembled by threading the locking sleeve into the forward part 3 of the receiver from the rear, threading 10 the catch 59 through the receiver to lock the sleeve in position, mounting the ejector as above described, and then mounting the sear on the depending lugs 75 by means of the pin 72. The frame and receiver groups 15 are attached to the stock by means of the screws 16 and 17, and the lubricant cup 18 is then threaded over the screw 17.

The bolt unit is assembled by slipping the sleeve 44 over the firing pin from the front, 20 slipping the spring 47 over the firing pin from the front and threading the constricted end of the spring over the collar 48, sliding the sleeve forwardly on the firing pin against the action of spring 47 and turning 25 the sleeve to catch over the downwardly projecting lug on the firing pin, inserting the firing pin unit into the bolt from the rear and screwing the sleeve 44 into the bolt, and then uncatching the firing pin from the 30 rear face of the sleeve 44 and permitting it to jump forward under the action of the spring 47, the lug 45 moving in a longitudinal slot on the lower side of the sleeve as shown in Fig. 6.

35 The recoil unit is assembled by mounting the buffer in the rear end of the recoil tube 4, slipping the shutter 29 into the recoil tube, inserting the recoil spring into the shutter, hooking the rear end of the recoil 40 spring into the rear end of the recoil tube, hooking the forward end of the recoil spring into the rear end of the bolt, turning the tube to the right relatively to the bolt to twist the spring, then retracting the bolt 45 into the recoil tube with the actuator 7 sliding down the slot 28 and hooking the actuator over the shoulder provided at the rearward end of the slot 28 as shown in Fig. 2.

The bolt and recoil units, thus assembled 50 together, are then inserted into the receiver from the rear, with the interrupted threads on the tube 4 (Fig. 17) clearing the interrupted threads at the rearward end of the part 3 of the receiver, and then turning the 55 recoil tube to the right one-eighth turn to interengage the aforesaid interrupted threads, the stud 61 of the catch 59 locking the two parts of the receiver against rotation.

60 The operation is as follows: With the parts in the position shown in Figs. 5 and 6, the gun is ready to fire. Upon pulling the trigger, the trigger bar 64 rocks the sear 66 in a clockwise direction until the lug 45 of the firing pin is disengaged by the sear,

whereupon the firing pin is shot forwardly by the spring 47. The circumferential obliquity of the abutting surfaces of the locking lugs is such that the breech pressure will not unlock the bolt at high breech pressure but will unlock the bolt when the pressure has dropped to a relatively low value. The oblique lower end 27' of the slot 27 is inclined to a plane perpendicular to the axis of the gun at substantially the same angle 75 as the abutting surfaces of the locking lugs so that in the unlocking rotation of the bolt the actuator lug 37 may move freely along this oblique slot 27'. After the bolt has rotated sufficiently to clear the locking lugs 80 from each other the actuator lug 37 reaches the bend in the slot 27, and in the continued rotation of the bolt the movement of the lug 27 along this bend gradually blends the rotary movement of the bolt into the purely 85 reciprocatory movement acquired when the lug 37 reaches the longitudinal slot 28. In the unlocking rotation of the bolt, the cam 42 on the rear end of the bolt engages the beveled face 46 on the firing pin lug and retracts the firing pin, the firing pin being held retracted by the cam 42 during the recoil of the bolt. When the bolt again reaches forward position the firing pin lug 45 engages behind the sear 66 before the 90 cam 42 disengages the firing pin in the locking rotation of the bolt. The firing pin is prevented from rotating with the bolt by the lug 45 extending through the slot 32 in the receiver. In the locking movement of 100 the bolt the firing pin lug 45 is accommodated by recess 33 extending in a counterclockwise direction from the slot 31. The tubular shutter 29 is caused to rotate with the bolt by the actuator lug 37 extending 105 through the rectilinear slot 30.

In the forward movement of the bolt the actuator lug 37 engages the bend in the slot 27, thereby gradually and smoothly setting the bolt into rotation without substantial 110 impact; and the locking lugs on the bolt and receiver respectively are spaced circumferentially in the unlocked position of the bolt, so that this combined reciprocatory and rotary motion of the bolt does not 115 bring the lugs on the bolt and receiver into engagement. However, when the lug 37 reaches the oblique portion 27' of the slot 27, which portion has substantially the same obliquity as the abutting faces of the locking lugs, the locking lugs of the bolt are carried into engagement with the locking lugs on the receiver. 120

In the unlocking movement of the bolt, the cam 74 (Figs. 10 and 12) moves the disconnector 67 downwardly, and the disconnector in turn moves the trigger bar 64 downwardly below the sear so that the sear is released whether or not the trigger is released. 130

According to the present invention extensive locking surfaces between the bolt and receiver are provided, and at the same time the weight and size of the parts are kept 5 within low limits. The bolt stroke and consequently the receiver are short and the weights are well to the rear. By dividing the receiver into two parts and interrelating the parts in the manner described, the 10 major portion of the receiver may be made very light, thereby greatly reducing the total weight of the gun. By constructing and arranging the frame 6 as described, it serves to form both the magazine and the 15 trigger guard and also a support for the firing mechanism.

I claim:—

1. A gun comprising a receiver, a breech closure movably disposed in the receiver to 20 reciprocate rearwardly and forwardly and to rotate at the forward end of its stroke into locked position, the receiver and closure having locking abutments arranged to interengage when the closure rotates into locked position, and having an interfitting 25 lug and guideway to guide the closure, the locking abutments being inclined to the line of breech pressure at such angles as to hold the bolt closed at high breech pressure and 30 to slide relatively to each other when the pressure drops to a low value automatically to unlock the closure, the guideway having a longitudinal portion and a transverse portion tangentially connecting with the longitudinal 35 portion throughout a gradual and uninterrupted bend so that the rotation of the closure into and out of locked position blends with its reciprocation smoothly and without impact, and the lug and guideway being 40 coordinated with the locking abutments so that the abutments are guided into and out of locking engagement throughout a smoothly curving path.

2. A gun comprising a receiver, a breech closure movably disposed in the receiver to 45 reciprocate rearwardly and forwardly and to rotate at the forward end of its stroke into locked position, the receiver and closure having locking abutments arranged to interengage when the closure rotates into locked 50 position and having an interfitting lug and guideway to guide the closure, the locking abutments being inclined to the line of breech pressure at such angles as to hold the bolt closed at high breech pressure and 55 to slide relatively to each other when the pressure drops to a low value automatically to unlock the closure, the guideway having a longitudinal portion and a transverse portion 60 tangentially connecting with the longitudinal portion throughout a gradual and uninterrupted bend so that the rotation of the closure into and out of locked position blends with its reciprocation smoothly and without impact, and said lug and guideway 65

being interrelated with said abutments so that the bolt may be rotated through an angle at least of the order of 110°.

3. A gun comprising a receiver, a breech closure movably disposed in the receiver to 70 reciprocate rearwardly and forwardly and to rotate at the forward end of its stroke into locked position, the receiver and closure having locking abutments arranged to interengage when the closure rotates into locked 75 position and having an interfitting lug and guideway to guide the closure, the locking abutments being inclined to the line of breech pressure at such angles as to hold the bolt closed at high breech pressure and to 80 slide relatively to each other when the pressure drops to a low value automatically to unlock the closure, the guideway having a longitudinal portion and an oblique portion joined together by a gradual and uninterrupted bend so that the rotation of the closure into and out of locked position blends with its reciprocation smoothly and without impact, and said lug and guideway being 85 interrelated with said abutments so that 90 said bend extends circumferentially through an angle at least of the order of 40°.

4. A gun comprising a receiver, a breech closure movably disposed in the receiver to 95 reciprocate rearwardly and forwardly and to rotate at the forward end of its stroke into locked position, the receiver and closure having locking abutments arranged to interengage when the closure rotates into locked position and having an interfitting 100 lug and guideway to guide the closure, the locking abutments being inclined to the line of breech pressure at such angles as to hold the bolt closed at high breech pressure and to slide relatively to each other when the pressure drops to a low value automatically to unlock the closure, the guideway having a longitudinal portion and an oblique portion joined together by a gradual and uninterrupted bend so that the rotation of the closure into and out of locked position blends with its reciprocation smoothly and without impact, said lug and guideway being 105 interrelated with said locking abutments so that said bend and oblique portion extend 110 circumferentially through angles at least of the order of 40° and 70° respectively.

5. A gun comprising a receiver, a bolt adapted both to reciprocate and to rotate in the receiver, locking lugs on the receiver 115 and bolt adapted to interengage when the bolt is rotated in one direction and to disengage when the bolt is rotated in the other direction, the engaging faces of said lugs being inclined to the line of breech pressure at such angle as to lock the bolt closed at high breech pressure, and to slide relatively to each other when the pressure drops to a low value automatically to unlock the bolt, and an interfitting guiding lug and 120

125

130

- guideway on the bolt and receiver respectively, the guideway having a longitudinal portion and an oblique portion inclined to the line of breech pressure substantially at 5 said angle, so as to guide the bolt in its reciprocation and to rotate the bolt at the end of its forward stroke to interengage said locking lugs, said longitudinal and oblique portions being joined by a gradual 10 bend extending through a wide circumferential angle so as smoothly to blend the reciprocatory and rotary movements of the bolt, and the locking lugs being circumferentially separated from each other in the 15 unlocked position of the bolt by a wide angle so as to clear each other during said blending.
6. A gun comprising a receiver, a bolt adapted to reciprocate rearwardly and forwardly in the receiver and to rotate into 20 locked position at the forward end of its stroke, the receiver having a slot extending longitudinally of the gun throughout its rearward portion and inclining circumferentially at its forward end, a lug on the bolt adapted to slide in said slot to guide the bolt in its reciprocatory and rotary movement, and a shutter rotatable with the bolt to close said slot, said shutter having a 25 longitudinal slot to accommodate said lug.
7. A gun comprising a receiver, a bolt adapted to reciprocate rearwardly and forwardly in the receiver and to rotate into locked position at the forward end of its 30 stroke, the receiver having a slot extending longitudinally of the gun throughout its rearward portion and inclining circumferentially at its forward end, a lug on the bolt adapted to slide in said slot to guide the bolt in its reciprocatory and rotary movement, and a shutter non-reciprocatable but 35 rotatable with the bolt to close said slot, said shutter having a longitudinal slot to accommodate said lug.
- 40 8. A gun comprising a receiver, a bolt adapted to reciprocate rearwardly and forwardly in the receiver and to rotate into locked position at the forward end of its stroke, the receiver having a slot extending longitudinally of the gun throughout its rearward portion and inclining circumferentially at its forward end, a lug on the bolt adapted to slide in said slot to guide the bolt in its reciprocatory and rotary movement, and a tubular shutter fitting 45 between said bolt and said receiver for covering said slot, said shutter having a longitudinal slot to accommodate said lug.
9. A gun comprising a receiver, a bolt 50 adapted to reciprocate rearwardly and forwardly in the receiver and to rotate into locked position at the forward end of its stroke, a firing member adapted to reciprocate with the bolt, the receiver having a bolt slot extending longitudinally of the gun 55

throughout its rearward portion and inclining circumferentially at its forward end, a lug on the bolt adapted to slide in said slot to guide the bolt in its reciprocatory and rotary movement, said receiver also having a firing member slot extending longitudinally thereof, a lug on the firing member extending through said last slot, and a shutter arranged to close both of said slots when the bolt is in locked position. 75

10. A gun comprising a receiver, a bolt adapted to reciprocate rearwardly and forwardly in the receiver and to rotate into locked position at the forward end of its stroke, a firing member adapted to reciprocate with the bolt, the receiver having a bolt slot extending longitudinally of the gun throughout its rearward portion and inclining circumferentially at its forward end, a lug on the bolt adapted to slide in said slot to guide the bolt in its reciprocatory and rotary movement, said receiver also having a firing member slot extending longitudinally thereof, a lug on the firing member extending through said last slot, and a tubular shutter fitting between said bolt and receiver for closing both of said slots when the bolt is in locked position, said shutter having slots to accommodate said lugs. 80

11. A gun comprising a receiver, a bolt adapted to reciprocate rearwardly and forwardly in the receiver and to rotate into locked position at the forward end of its stroke, a firing member adapted to reciprocate but not rotate with the bolt, the receiver having a bolt slot extending longitudinally of the gun throughout its rearward portion and inclining circumferentially at its forward end, a lug on the bolt adapted to slide in said slot to guide the bolt in its reciprocatory and rotary movement, said receiver also having a firing member slot extending longitudinally thereof, a lug on the firing member extending through said last slot, and a shutter arranged to rotate but not reciprocate with said bolt for closing both of said slots when the bolt is in locked position, said shutter having slots arranged to register with said receiver slots when the bolt is unlocked to accommodate said lugs. 95

12. A gun comprising a receiver, a bolt adapted to reciprocate rearwardly and forwardly in the receiver and to rotate into locked position at the forward end of its stroke, a firing member arranged to reciprocate but not rotate with the bolt, the receiver having a bolt slot extending longitudinally of the gun throughout its rearward portion and inclining circumferentially at its forward end, a lug on the bolt adapted to slide in said slot to guide the bolt in its reciprocatory and rotary movement, said receiver also having a firing member slot extending longitudinally thereof, a lug on the firing member extending through said last slot 100

- slot, and a tubular shutter fitting between said bolt and receiver for closing said slots when the bolt is in locked position, said shutter being rotatable but non-reciprocatable 5 with said bolt and having slots for said lugs arranged to register with said receiver slots when the bolt is unlocked, the shutter slot for the firing member lug having an offset portion to permit rotation of the shutter 10 with the bolt into locked position.
13. A gun comprising a receiver, a bolt adapted to reciprocate rearwardly and forwardly in the receiver and to rotate into locked position at the end of its forward 15 stroke, said bolt having a lug to guide its movements, the forward portion of said receiver connecting with the barrel of the gun and the rearward portion comprising a tube threaded to the forward portion, said portions 20 having intercommunicating slots to guide said lug, and a second tube rotatable within said first tube for closing said slots when the bolt is in locked position, said tube having a slot for said lug adapted to register with said slot when the bolt is unlocked, 25 said second tube abutting at its forward end against the rearward end of the forward portion of the receiver and against the rearward end of said first tube at its rearward 30 end.
14. A gun comprising a receiver, a bolt adapted to reciprocate rearwardly and forwardly in the receiver and to rotate into locked position at the end of its forward 35 stroke, said bolt having a lug to guide its movements, the forward portion of said receiver connecting with the barrel of the gun and the rearward portion comprising a tube secured to the forward portion, said portions 40 having intercommunicating slots to guide said lug, and a second tube rotatable within said first tube for closing said slots when the bolt is in locked position, said second tube having a slot for said lug adapted to register with the slot of said first tube when the 45 bolt is unlocked.
15. A gun comprising a receiver, a bolt arranged to reciprocate forwardly and rearwardly in the receiver and to rotate into locked position at the forward end of its stroke, the bolt having a lug to guide its movement, the receiver comprising forward and rearward portions connected end to end, 50 said portions having intercommunicating slots to guide said lug, the slot in said rearward portion extending longitudinally of the gun to guide the reciprocation of the bolt and the slot in the forward portion bending circumferentially to rotate the bolt into and 55 out of locked position, the forward portion having a thick wall to withstand the stresses incident to the rotation of the bolt and the rearward portion having a lesser thickness adapted merely to guide the bolt in its reciprocatory movement.
16. A gun comprising a receiver having tubular forward and rearward portions disposed end to end, a tubular locking member fitted into said forward portion, said rearward portion being fitted into said forward 70 portion in abutting relationship to said member, and a tubular shutter rotatable in said rearward portion in abutting relationship to said member.
17. A gun comprising a receiver having tubular forward and rearward portions disposed end to end, a tubular locking member fitted into said forward portion, said rearward portion being fitted into said forward portion in abutting relationship to said member, and a bolt movable in said receiver into and out of locking relationship to said member. 80
18. A gun comprising a receiver having tubular forward and rearward portions detachably fitted together end to end, a tubular locking member fitted into said forward portion, and a bolt movable in said receiver into and out of locking relationship with respect to said member, said receiver and bolt 85 having interlocking abutments adapted to lock the bolt in closed position, and certain of said abutments having lubricant ducts leading to the abutting surfaces thereof.
19. A gun comprising a receiver, a bolt 90 reciprocatable forwardly and rearwardly in the receiver and rotatable into locked position at the forward end of its stroke, and sets of interengaging locking abutments on the receiver and bolt respectively to lock the bolt 95 in closed position, one of said sets of abutments being provided with lubricant ducts leading to the abutting faces thereof.
20. A gun comprising a receiver, a breech closure movably disposed in the receiver to 100 reciprocate rearwardly and forwardly and to rotate at the forward end of its stroke into locked position, the receiver and closure having locking abutments arranged to interengage when the closure rotates into locked position and having an interfitting lug and guideway to guide the closure, the locking abutments being inclined to the line of breech pressure at such angles as to hold the bolt closed at high breech pressure and to 105 slide relatively to each other when the pressure drops to a low value automatically to unlock the closure, the guideway having a longitudinal portion and an oblique portion joined together by a gradual and uninterrupted bend so that the rotation of the closure into and out of locked position blends with its reciprocation smoothly and without impact, and said lug and guideway being 110 interrelated with said abutments so that said bend extends circumferentially through an angle at least of the order of one-half the circumferential extent of said locking abutments. 115
21. A gun comprising a receiver, a breech 120
- 125
- 130

closure movably disposed in the receiver to reciprocate rearwardly and forwardly and to rotate at the forward end of its stroke into locked position, the receiver and closure 5 having locking abutments arranged to inter-engage when the closure rotates into locked position and having an interfitting lug and guideway to guide the closure, the locking abutments being inclined to the line of breech 10 pressure at such angles as to hold the bolt closed at high breech pressure and to slide relatively to each other when the pressure drops to a low value automatically to unlock the closure, the guideway having a longi-

tudinal portion and an oblique portion joined 15 together by a gradual and uninterrupted bend so that the rotation of the closure into and out of locked position blends with its reciprocation smoothly and without impact, said lug and guideway being interrelated 20 with said locking abutments so that said bend and oblique portion extend circumferentially through angles whose ratio is approximately four-sevenths.

Signed by me at Cleveland, Ohio, this 25 18th day of December, 1919.

OSCAR V. PAYNE.
